UNITED STATES PATENT OFFICE.

LOTHAR VON GRAVE, OF WALLINGFORD, CONNECTICUT, ASSIGNOR TO THE
H. L. JUDD & COMPANY, OF NEW YORK, N. Y.

DESIGN FOR A MIRROR-FRAME, &c.

SPECIFICATION forming part of Design No. 23,384, dated June 19, 1894.

Application filed May 1, 1894. Serial No. 509,721. Term of patent 3½ years.

To all whom it may concern:

Be it known that I, LOTHAR VON GRAVE, a subject of the Emperor of Germany, and a resident of Wallingford, New Haven county, State of Connecticut, have invented and produced a new and original Design for Frames for Looking-Glasses, &c., of which the following is a specification, reference being had to the accompanying drawing, wherein the figure shows a face view of a frame illustrating my design, one half only being shown in full detail, the other half being shown in outline.

The essential features of my design consist in a central rectangular portion surrounded by an open-work ornamental border following the general contour of the central rectangular portion and an open-work ornamental stand at the lowest corner of the frame.

In the drawing *a* represents a central ornamental rectangular portion, provided with an opening *b*. Surrounding this portion *a* *b* is an open work ornamental border consisting of the open-work shield-like grill ornaments *c* *c*, the open-work corner ornaments *d* and *e* the adjacent, intervening open-work scroll ornaments *f*, *g*, *h*, *i*; the open-work base corner ornament *k* and the legs *l* *m* forming the stand.

What I claim is—

The design for frames for looking glasses, &c., substantially as shown and described.

LOTHAR VON GRAVE.
